G. A. CARLSON.

CURTAIN ROD.

APPLICATION FILED OCT. 28, 1918.

1,315,705.

Patented Sept. 9, 1919.

Inventor:

Gustaf A. Carlson,
Bydgoszcz, Poland.

UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

CURTAIN-ROD.

1,315,705.

Specification of Letters Patent.

Patented Sept. 9, 1919.

Application filed October 28, 1918. Serial No. 259,966.

To all whom it may concern:

Be it known that GUSTAF A. CARLSON, a citizen of Sweden, who has taken out first papers for citizenship in the United States, 5 residing at Chicago, in the county of Cook and State of Illinois, has invented a new and useful Improvement in Curtain-Rods, of which the following is a specification.

This invention relates particularly to flexible curtain-rods, or curtain-rods provided with resilient flexible portions, such as are commonly employed for sash-curtains.

Curtain-rods of the type here referred to comprise close-wound spring wire coils; 15 and the primary object of the invention is to provide an improved connection between the close-wound spiral and a bracket which is adapted to be mounted on the window-frame, or sash, as desired.

20 The invention is illustrated in its preferred embodiment in the accompanying drawing, in which—

Figure 1 represents a broken plan view, illustrating the manner in which the curtain-rod is mounted on a window-frame, or sash; Fig. 2, a broken elevational view of the same; Fig. 3, an inner elevational view of the bracket employed in the construction shown in Figs. 1 and 2; Fig. 4, a fragmentary view of the curtain-rod and the gripper element employed in connection therewith; Fig. 5, a sectional view of the parts illustrated in Fig. 4; Fig. 6, a broken elevational view showing a sash, or frame, 35 equipped with a bracket of modified form; and Fig. 7, a perspective view of the bracket shown in Fig. 6.

In the construction illustrated, A represents a window-frame, or sash; and B, the 40 improved curtain-rod applied thereto.

The device B comprises a close-wound wire coil 1; a pair of brackets 2 adapted to be mounted on the frame, or sash; and a pair of grippers 3, joining the extremities 45 of the coil 1 to the brackets 2.

The brackets 2 may be of any approved form. As shown, each bracket comprises a base-portion 2^a adapted to be secured to the frame, or sash, A, as by means of screws; 50 and an arm 2^b which is curved and provided with a loop 2^c, which is formed by re-curving the end-portion of the arm back and under the body-portion, the extremity being indicated at 2^d.

55 The front wall of the loop 2^c is provided

with an enlarged opening 4 which communicates with a reduced opening, or perforation, 4^a, in the end of the loop, thus forming what is, in effect, a T-slot for the reception of the gripper member 3. 60

The gripper member 3 is in the nature of a pair of spring jaws 3^a, which are connected by a curved resilient web 3^b. The gripper device may be formed from resilient sheet-metal, curved to form the ring 3^b and the 65 arms of the jaws. The arms of the jaws are curved to afford substantially semi-cylindrical portions which embrace the end of the coil 1; and the extremities of the jaws are provided with inturned flanges 3^c which 70 conform to the spiral of the coil 1, so that the gripper member 3 may be turned upon the spiral, as a nut is turned upon a screw. The semi-cylindrical portions of the gripper diverge somewhat in forming a junction with the ring-portion 3^b, as indicated at 3^d. Thus, the ring-portion of the gripper is larger than the diameter of the concavo-convex gripper arms. 75

Assuming the flexible rod 1 to be equipped 80 at each end with one of the grippers 3, the rod may be connected with the brackets by introducing the enlarged portion of the gripper through the enlarged opening 4, and seating the concavo-convex arms of 85 the gripper in the rounded socket 4^a. Usually, the rod is made a little shorter than the space between the brackets, so that the rod will be placed somewhat under tension. The effect is that the coil tends to 90 draw the grippers through the sockets 4^a, and the walls of the socket, engaging the tapering portions 3^d of the gripper arms, force the jaws more securely into engagement with the convolutions of the coil. 95

It is not essential to the invention that the rod 1 should be wholly constructed of coiled wire. Usually piano steel wire is employed in making a spiral coil of this character, and it may be desirable to construct the rod with wire coils at its end portions only, as shown in my co-pending application No. 259,965, filed of even date herewith. 100

In Figs. 6 and 7, there is illustrated a 105 bracket 5, which is adapted to be applied either to the front face of a frame A¹, or to the inner edges of the side members of the frame, as illustrated in Fig. 6. This bracket comprises a base 5^a adapted to be secured 110

to the frame by means of screws; a flange, or web 5^b, extending at right-angles to the base; and a flange 5^c extending parallel with the base and disposed over or above it, so that the bracket is in effect a U-shaped bracket. The flange 5^c is provided with an open socket 6, which communicates, through a slot 6^a, with a socket 6^b in the web 5^b. Each of the sockets 6 and 6^b is of the proper size to engage the concavo-convex arms of the gripper device 3, and to hold the gripper device in the same manner as does the socket 4^a of the bracket 2. When the bracket 5 is applied to the sash, or frame, in the manner shown in the upper portion of Fig. 6, the end-portion of the flexible rod may be passed through the slot 6^a and the gripper enter in the socket 6^b; and when the bracket 5 is applied in the manner shown in the lower portion of Fig. 6, the grippers 3 may be introduced into the sockets 6 of the flanges 5^c; the sockets 6, in this case, serving to hold the grippers.

From the description given, it will be understood that the improved device comprises, in combination with a flexible rod-section, a gripper element and a supporting bracket which has a socket for the gripper element, which tends to hold the gripper closed when the rod is under tension. The construction described is simple and inexpensive, and enables the curtain-rod to be applied to and removed from the brackets with the greatest facility.

It will be noted from Fig. 4 that the concavo-convex arms of the gripper which embrace the end-portion of the coil, cover, when considered together, considerably more than one-half of the circumference of the coil, and the sloping portions 3^a of the ring-portion of the gripper likewise cover more than a half portion of the circumference of the coil. The purpose is to insure proper contact between the sloping portions of the gripper and the walls of the socket, so that proper engagement will be effected between the gripper and the socket, regardless of angular rotation of the gripper member within the socket. This feature makes it unnecessary to pay any attention to the matter of the angular rotation of the gripper within the socket, because of the slot which communicates with the socket, inasmuch as the proper wedging action will be secured in the socket regardless of the plane occupied by the ring 3^b of the gripper with relation to the slot leading to the socket which engages the gripper.

The foregoing detailed description has

been given for clearness of understanding 60 only, and no unnecessary limitations should be understood therefrom, but the appended claims should be construed as broadly as permissible, in view of the prior art.

What I regard as new, and desire to set 65 out by Letters Patent, is:

1. In means of the character set forth, the combination of a bracket provided with a socket, a coil-spring, and a gripper engaging said socket and having jaws engaging 70 the coil-spring, the engagement between said socket and gripper being such as to tend to hold the jaws of the gripper in closed position.

2. In means of the character set forth, the 75 combination of a coil-spring, a gripper having jaws engaging said spring and having an enlarged web-portion, and a bracket having a socket embracing the web-portion of said gripper and tending to hold the jaws 80 in closed position.

3. In means of the character set forth, the combination of a coil-spring, a gripper comprising jaws and an enlarged resilient ring connecting said jaws, and a bracket provided with a socket adapted to embrace 85 said jaws and engage the ring-portion of the gripper.

4. In means of the character set forth, the combination of a coil-spring, a gripper comprising a pair of jaws and a resilient ring connecting said jaws, and a bracket provided with a socket adapted to permit 90 said jaws to extend therethrough, said bracket having an opening leading from said 95 socket, which enables the gripper to be introduced into the socket while the bracket is attached to a frame.

5. In means of the character set forth, the combination of a coil-spring, a gripper applied thereto comprising a pair of 100 jaws and a ring connecting said jaws, and a bracket comprising an arm provided with a loop having a socket in its end-portion and having an enlarged opening communicating 105 with said socket, whereby the ring-portion of the gripper may be introduced through said enlarged opening.

6. In means of the character set forth, a bracket comprising a base flange equipped 110 with means for attachment to a frame, a web projecting from said base flange and provided with a socket, and a flange extending from said web parallel with the base flange and provided with a socket, said sockets being connected by a slot. 115

GUSTAF A. CARLSON.
